CENTRALIZED TRAFFIC CONTROLLING SYSTEM FOR RAILROADS

Darrol F. De Long and Frederick W. Brixner,
Rochester, N. Y., assignors to General Railway
Signal Company, Rochester, N. Y.

Application August 30, 1933, Serial No. 687,477

15 Claims. (Cl. 246—3)

This invention relates to centralized traffic controlling systems for railroads and more particularly to the communication part of such systems.

5 A centralized traffic controlling system, as contemplated by the present invention, provides a means whereby railroad traffic is controlled from a central office and whereby the operator at the central office may be informed concerning the 10 location of trains and the condition of the devices of the system which are arranged to govern the movement of such trains. Such a system is supplemental to local automatic block signals to prevent unsafe train movements, improper operation 15 of track switches or the like.

The switches and signals are distributed throughout the territory, but those located relatively near or adjacent each other as well as the apparatus provided to govern these switches and 20 signals are conveniently referred to as comprising a field station. A communication system is provided to interconnect the central control office with the several field stations and is so organized that the operator obtains complete supervision 25 of the various signals and switch devices at the remote stations.

The present invention is more particularly concerned with the organization of the circuits at the 30 field station in a system of the two-wire double capacity type. By double capacity is meant that indications are transmitted during the operating cycle of the communication system during both the "on" and "off" periods, that is, during the periods when the line circuit is energized and also 35 during the periods when the line circuit is de-energized.

In accordance with the present invention, the two-wire line circuit of the communication system connects the control office and the several 40 field stations in series. The line circuit includes a line relay and the contacts of two impulse relays at each field station. At the end field station, the conductors of the line are connected together to complete the two-wire circuit.

45 These two line conductors form a single circuit which is used to select a desired one of the field stations, after which the signals or switch devices at the selected station may be actuated or conditioned for governing the traffic as determined by 50 the manual operation in the control office. Since the present invention is not concerned with the transmission from the control office to the various field stations, which is commonly referred to as the transmission of controls, this portion of the 55 system has been omitted from the present disclosure.

The communication system is also used to transmit indications to the control office for registering a particular station in the office and 60 thereafter indicating the presence or absence of

trains in particular track sections, the positions of track switches, as well as any other indications which may be useful in directing and supervising train movements. This particular function of the communication system is automatically effected when a new indication is ready to be transmitted to the control office and is conveniently referred to as the transmission of indications.

5 The present invention is applied to a system of the coded duplex type such, for example, as disclosed in the prior application of N. D. Preston, et al, Ser. No. 645,037 filed November 30, 1932, corresponding to British Patent #425,925 of 1932. In this type of system, the transmission of controls and the transmission of indications can occur on separate cycles of operation or they can 10 occur during the same cycle of operations.

15 When indications are transmitted, the field station transmits a station registering code for registering this particular station in the control office. Thereafter, the particular indications, as determined by the positions of the various devices at this particular station, are transmitted by means of additional code impulses, which 20 register the indications in the control office by means of indicator devices such as lamps or the like associated with the sending station.

25 The duration or length of time during the "off" and "on" impulse periods of a cycle in the above-mentioned prior application are used to form a characteristic code combination which determines the particular station to be registered in the control office and the particular indications to be transmitted after such registration. Since the 30 present invention is more particularly concerned with the manner in which stations are allotted the use of the communication system during a cycle of operations and since it is not necessary for an understanding of the present invention to disclose the various control office circuits, that portion of the communication system located in the control office is shown in abbreviated form.

35 In the above-mentioned prior application Ser. No. 645,037, the lock-out relay feature is disclosed, 45 whereby only one station can actively associate itself with the communication line by picking up a lock-out relay associated with this particular station at the beginning of an operating cycle. After the cycle is once initiated in this prior system, only one station lock-out relay can be up at 50 any one time. With this type of lock-out arrangement the stations are given preference in accordance with their geographic location, that is, when two or more stations attempt to transmit 55 indications at the same time, the one nearest the control office has preference and the others are locked out.

60 One feature of the present invention relates to the superiority-of-code type of lock-out. In this

type of system when two or more stations have indications to transmit at the same time, the station selecting or SI relays at all of such stations are picked up and are dropped during the transmission of the station registering code until at the end of the station registering code the SI relays have all dropped except at one station. The SI relays of inferior stations are dropped out during the code transmitting portion of this cycle as determined by their particular code combinations as formed by the connections of their code jumpers.

The superiority-of-code type of lock-out arrangement has been applied to a two-wire line circuit, as for example, in the prior application of T. J. Judge, Ser. No. 635,062 filed September 27, 1932, corresponding to British Patent #419,401 of 1932. In this prior application, however, indications are not of the double-capacity type, but are only transmitted during the "off" (de-energized) periods of the line circuit. The present invention provides the superiority-of-code type lock-out in a two-wire system of the double-capacity type.

Other objects and advantages of the present invention will be hereinafter set forth in the specification and claims and shown in the drawings. The characteristic features will be explained more in detail in the following description of one embodiment of the invention while the various other characteristic features and advantages of the system comprising this invention will be in part pointed out and in part apparent as the description progresses.

In describing the invention in detail reference will be made to the accompanying drawings which illustrate in a diagrammatic manner the apparatus and circuits employed. Those parts having similar features and functions are designated by like letter reference characters generally made distinctive either by the use of distinctive exponents representative of their location or by the use of suitable preceding numerals representative of the order of their operation, and in which:—

Figs. 1A and 1B illustrate a portion of the apparatus and circuits employed at a typical field station.

Figs. 2A and 2B illustrate an additional portion of the apparatus and circuits employed at the same typical field station.

Within the rectangle bounded by the dash line in the upper left-hand portion of Fig. 1A, a very small portion of the control office circuits are illustrated to indicate that the two-wire line circuit is normally energized from the control office battery, and to indicate how this battery is reversibly connected to the line circuit for transmitting controls, and how the line circuit is de-energized by the operation of the line impulsing relay.

General description

The operation of the circuits may be conveniently followed by placing Figs. 2A and 2B below Figs. 1A and 1B, with Fig. 1B to the right of Fig. 1A and with correspondingly numbered lines in alignment. It will be understood that the two-wire line circuit extends through the other stations of the system, the connections of which are practically the same as those illustrated in the present drawings. As will be more specifically pointed out in the following description, the points of difference in the circuit connections at the different field stations are the distinctive

connections of the code jumpers so that a particular field station transmits an individually distinctive code combination of impulses.

For the purpose of simplifying the illustrations and facilitating in the explanation various parts and circuits have been diagrammatically shown and certain conventional illustrations have been employed. The drawings have been made more with the purpose of making it easy to understand the principles and mode of operation rather than with the idea of illustrating the specific construction and arrangement of parts that would be employed in practice. Thus, the various relays and their contacts are illustrated in a conventional manner, the use of symbols being employed to indicate the connections to the terminals of batteries or to the sources of current instead of showing all of the wire connections to these terminals.

The symbols (+) and (−) indicate the positive and negative terminals respectively of suitable batteries or other sources of current, and the circuits with which these symbols are used always have current flowing in the same direction. No attempt has been made to show all of the apparatus employed or its exact arrangement at the field stations, since this may vary to suit local conditions. The character of that portion of the control office and field station apparatus illustrated will now be considered.

Office and station equipment

As typical of the equipment located in the control office whereby the line circuit is energized with (+) or (−) impulses, a positive control relay PC and a negative control relay NC are indicated. Line relay F is connected in series with one wire of the two-wire line circuit and this wire is arranged to be intermittently impaled by means of pulsing relay PL.

The communication part of the system at the field station includes a three-position biased-to-neutral polarized line relay F¹ together with its quick acting line repeating relay FP¹. Relay F¹ is normally positioned to the right by reason of the normally energized line wire 1 to which the (+) terminal of control office battery B is connected. Relay FP¹ is normally deenergized. Slow acting relays SA¹ and SAP¹ are provided to define the bounds of each cycle of operations. Relay SA¹ is sufficiently slow releasing so that it holds its armature attracted during all "off" periods (irrespective of the length of the "off" periods) except the last or "change to normal" period which is sufficiently long to allow relays SA¹ and SAP¹ to drop their contacts.

The field station includes a bank of stepping relays 1V¹, 2V¹, 3V¹, 4V¹ and the associated half-step relay VP¹. For the purpose of illustrating the manner in which the long and short "on" and "off" periods of a cycle of operations are determined and provided during a cycle of operations, relays PT¹, PF¹ and PB¹ are illustrated in Fig. 2A. The jumper connections illustrated in Fig. 2B determine the length of the "off" and "on" periods of the line circuit, as will be specifically pointed out later in the description.

For the purpose of illustrating the manner in which the stations are selectively associated and disassociated with the line circuit during a cycle of operations, two SI relays, 1SI¹ and 2SI¹ are shown in Fig. 1A. Relay 1SI¹ is selectively maintained energized during the "off" periods and relay 2SI¹ is selectively maintained energized

during the "on" periods of the line circuit during an operating cycle.

For the purpose of illustrating the manner in which the length of the "off" and "on" periods are checked at a particular field station to determine if the particular code being transmitted matches the code at this particular station, relays FT^1 , FTP^1 , BT^1 and BTP^1 are provided. Relay FT^1 checks the timing of the "on" periods and relay BT^1 checks the timing of the "off" periods, with the corresponding repeating relays FTP^1 and BTP^1 cooperating in a manner which will be fully pointed out later.

A change repeating relay CHP^1 is employed at each field station in connection with the indication circuit to determine when this field station is to transmit new indications. This relay is indicated with its control circuit omitted, but it will be understood that relay CHP^1 automatically registers a change in the condition of any device such as the track section, switch or signals and stores such a condition until an operating cycle has taken place to transmit indications of such condition to the control office. The circuit arrangement for relay CHP^1 is such that it is picked up to start a cycle of operations and is dropped at some point during this cycle so that it may be again energized when additional indications are to be transmitted. The circuit arrangement for relay CHP^1 may be of the type fully disclosed in the patent to De Long et al., No. 1,852,402 issued April 5, 1932, and to simplify the present disclosure it will not be explained in detail, but it may here be considered that its control wire 35 corresponds to wire 33 in the above mentioned patent.

It is believed that the nature of the present invention, its advantages and characteristic features may be best understood with further description being set forth in the manner of operation.

Operation

In the present system the single line circuit, consisting of the two line wires 7 and 9 extending from the control office to all field stations, is normally energized by a steady flow of direct current and the system may be initiated into a cycle of operations either at the control office or at any field station by means arranged to open this line circuit. The system then operates through the cycle, which consists of a definite number of impulses applied to the line at the control office and during this cycle new controls may be transmitted from the control office to any one field station, new indications may be transmitted from any one field station to the control office, or duplex transmission may be accomplished whereby both controls and indications are transmitted between the same or different field stations and the control office.

It is evident that in accomplishing duplex transmission over a single circuit, two distinctive code arrangements cannot be formed by selecting the character of the impulses alone, and consequently the system is so organized that codes for outbound transmission are formed by selecting the polarity of the impulses. As above mentioned, the manner in which this portion of the system operates is immaterial to an understanding of the present invention, therefore, it is not considered necessary to illustrate or describe the circuits employed for the transmission of controls.

75 The code arrangement for inbound transmis-

sion is formed by selecting the lengths of the energized and deenergized periods of the line, which for convenience are referred to as the "on" and "off" periods respectively.

In describing the operation of the system in detail, it is considered sufficient to briefly outline the functions of such parts as have been described in detail in previously mentioned applications. Also, in describing in detail the operations which will be considered as typical of the novel features of the present invention, it is convenient to discuss separately the groups of such operations in detail under the headings as indicated.

Normal period of rest

With the communication system, with which this invention is concerned, at rest, all of the relays illustrated in the drawings are in their normal or deenergized positions except the line relay and relay PT^1 of Fig. 2A. The control line conductor is normally energized over a circuit extending from the (+) terminal of battery B in the control office, front contact 26 of relay PC, back contact 27 of relay NC, winding of relay F, back contact 28 of relay PL, line conductor 7, winding of relay F^1 , back contact 62 of relay PF^1 , back contact 63 of relay PB^1 , line conductor 64 which extends through the other field stations in series, line conductor 9 returning through the other field stations in series, back contact 29 of relay NC and front contact 30 of relay PC to the (-) terminal of battery B. Relay F in the control office is of the neutral type and normally its contacts are in their picked up positions. Relay F^1 at the field station has its polar contacts positioned to the right as indicated.

Relay PT^1 is energized over a circuit extending from (+), contact 200 of relay F^1 in its right hand position, back contact 201 of relay SAP^1 and winding of relay PT^1 , to (-).

Operation of stepping relays

The stepping relays in the control office have not been illustrated and the stepping relays at the typically illustrated field station have only a portion of their control circuits shown. The operating circuits for these stepping relays have been omitted, but for the purpose of disclosing the present invention it will be assumed that they function in the same manner as disclosed in the above mentioned prior application Ser. No. 635,062. As in Ser. No. 635,062, the operation of the present system consists of cycles, each comprising a "starting" or momentary deenergized period of the line, followed by a "conditioning" or energized period of the line. Then follows a series of deenergized and energized periods of the line of variable lengths, as determined by the code being transmitted. For convenience, the deenergized periods of the line are referred to as "off" periods and the energized periods of the line are referred to as "on" periods.

The stepping relays are successively picked up during the "off" periods of a cycle (after the "start" period) and the VP^1 relay is shifted during the "on" periods of a cycle. More specifically, relay VP^1 is picked up during the conditioning "on" period and stuck up until the next "on" period. Relay $1V^1$ is picked up during the first "off" period, relay VP^1 is dropped during the first "on" period and relay $2V^1$ is picked up during the second "off" period. Relay VP^1 is picked up during the second "on" period and stuck up until the next "on" period. Relay $3V^1$ is picked up during

the third "off" period, relay VP^1 is dropped during the third "on" period and relay $4V^1$ is picked up during the fourth "off" period. The stepping relays $1V^1$ to $4V^1$, inclusive, are stuck up, when 5 picked up, until the clearing out "off" period at the end of the cycle.

It will be understood that contact 127 of relay FP^1 of Fig. 1A repeats the "off" and "on" periods of the line during impulsing. This contact and 10 the dotted line leading to the bracket embracing relays VP^1 to $4V^1$, inclusive, of Fig. 1B control the operation of these relays as above described and in the same manner that contacts 126 and 129 of relay FP^1 in Fig. 2 of Ser. No. 635,062 control 15 the operation of similar relays in this prior application.

The timing of the impulses ("on" periods) and the spaces between impulses ("off" periods) will now be briefly pointed out, reference being made 20 to British Patent No. 419,401 for a detailed explanation of this operation. The office opens the line at the end of an "on" period to mark the beginning of the next "off" period, by picking up relay PL . In response to the open line condition, relay F drops, then relay FP drops, then the stepping relay picks up, then relay E (shown in the above mentioned British patent but not shown in the present disclosure) drops, then relay PL drops and closes up the line to mark the beginning 25 of the next "on" period. In response to the closed line condition, relay F picks up, then relay FP picks up, then relay VP shifts (picks up or drops depending on whether it is down or up), then relay E picks up, then relay PL picks 30 up and opens the line to mark the beginning of the next "off" period. This operation of course makes the impulses and the time spaces of uniform length. During this application of the impulses to the line by the office apparatus, a transmitting station modifies these impulses and the time spaces between, to form codes by varying 35 their lengths.

Automatic start and conditioning

45 In connection with the present disclosure, consideration will be made to the manner in which indications alone are transmitted from a field station to the control office, since the circuit operation as far as the present invention is concerned 50 is the same when indications are transmitted during the same cycle that controls are transmitted outbound.

It will be assumed that relay CHP^1 of Fig. 1B is picked up in response to a change in condition 55 at the associated field station such as the occupancy of a track section or a movement of a traffic controlling device. A circuit is now closed for picking up relays $1SI^1$ and $2SI^1$ extending from (+), front contact 66 of relay CHP^1 , conductor 60 80, back contact 67 of relay SAP^1 , and the upper windings in series of relays $1SI^1$ and $2SI^1$, to (-). Relay $1SI^1$ closes a stick circuit for itself which is effective until relay $1V^1$ is picked up and which 65 extends from (+), back contacts 40, 41 and 42 of relays $3V^1$, $2V^1$ and $1V^1$, respectively, conductor 81, front contact 43 of relay $2SI^1$, front contact 44 and lower winding of relay $1SI^1$, to (-).

A circuit is now closed for picking up relay FT^1 , which extends from (+) front contact 45 of 70 relay $2SI^1$, back contact 46 of relay FP^1 , and winding of relay FT^1 , to (-). A circuit is also closed for picking up relay PB^1 which extends from (+), back contact 202 of relay $1V^1$, back contact 203 of relay VP^1 , conductor 82, front contact 75 204 of relay PT^1 , front contact 205 of relay

$2SI^1$, front contact 206 of relay $1SI^1$, back contact 207 of relay FP^1 and winding of relay PB^1 , to (-). Relay PB^1 closes a stick circuit for itself, extending from (+), front contact 208 of relay PT^1 , front contact 209 and winding of relay PB^1 , to (-).

The opening of back contact 63 of relay PB^1 deenergizes the line circuit which allows relays F and F^1 to drop to their neutral positions. The dropping of relay F in the control office effects 10 the picking up of relay STR , which in turn causes the dropping of relay PC and the picking up of relay NC for reversing the connection of battery B to the line circuit. The picking up of the start relay STR in the control office, which controls the 15 shifting of the PC and NC relays just mentioned, is effective to initiate the cycle of stepping operations in the control office. The operation of relay STR and the manner in which the line circuit is impulsed by relay PL is fully set forth in the 20 above mentioned prior application Ser. No. 645,037 and may be briefly explained as follows:

The dropping of relay F in response to the field station opening the line to start a cycle of operations, closes a pick-up circuit for relay STR (not shown) which extends through a back contact of the SA relay and a back contact of the F relay in the office. Relay STR is then stuck up until the end of the cycle. With relay STR up, the circuit shown in the upper left hand portion of 30 Fig. 1A of the present disclosure is shifted from the PC to the NC relay so that relay PC drops, relay NC picks up and remains up throughout the cycle. The SA and the SAP relays in the office (not shown) pick up in response to the picking up 35 of relay NC and the stepping relays in the office (not shown) operate through their cycle as previously mentioned. Relay PL is controlled by the response of the stepping relays and opens the line at back contact 28 (corresponding to back contact 3 in application 635,062) when the VP relay shifts during each "on" period and to close the line at back contact 28 when a stepping relay picks 40 up during each "off" period. During this impulsive, the control office normally applies a comparatively long "on" period to the line which can be changed to a short "on" or not as determined by the station which is transmitting. Similarly, the office normally applies a comparatively short "off" period to the line circuit which can be changed to a long "off" or not, as determined by the field station which is transmitting, all of which will be pointed out in detail in the following 45 description.

The picking up of relays $1SI^1$ and $2SI^1$ closes 55 a stick circuit for relay PT^1 which is independent of the above described pick-up circuit for this relay through back contact 291 of relay SAP^1 , which stick circuit is completed before relay F^1 drops to open the normally energized pick-up 60 circuit of relay PT^1 . This stick circuit extends from (+), through either front contact 210 or 211 of the relays $1SI^1$ and $2SI^1$ respectively, front contact 212 of relay PT^1 , back contact 213 of relay PB^1 and winding of relay PT^1 , to (-). At 65 the time relay F^1 opens its contact 200, the above described pick-up circuit for relay PT^1 is deenergized, but relay PT^1 momentarily remains in its picked up position until the opening of back contact 213 of relay PB^1 , which opens the stick circuit of relay PT^1 allowing this relay to drop.

The opening of front contacts 204 and 208 of relay PT^1 opens the above described pick-up and stick circuits of relay PB^1 which allows this relay 70 to drop. The dropping of back contact 63 of relay 75

PB¹ again energizes the line circuit to mark the end of the start "off" period and the beginning of the conditioning "on" period. During this conditioning "on" period, the line repeating and the 5 slow acting relays in the control office are conditioned, as disclosed in the above mentioned prior application Ser. No. 645,037. The line relays together with the line repeating and slow acting relays at all of the stations are likewise 10 conditioned during the conditioning "on" period.

The dropping of relay PC and the picking up of relay NC in the control office, as previously mentioned, has the effect of energizing line conductor 1 with a (−) potential (when relay PB¹ closes 15 its back contact 63) which is effective to position relay F¹ to the left and to pick up relay F in the office. A circuit is now closed for picking up relay FP¹ which extends from (+), contact 122 of relay F¹ in its left hand dotted position and winding of relay FP¹, to (−). A circuit is closed for 20 picking up relay PT¹ which extends from (+), front contact 214 of relay FP¹, back contact 213 of relay PB¹ and winding of relay PT¹, to (−). Relay PT¹ again closes the above described stick 25 circuit for itself including front contacts 210 and 211 of the SI relays, which stick circuit is independent of front contact 214 of relay FP¹.

A circuit is closed for picking up relay FTP¹ 30 which extends from (+), front contact 45 of relay 2SI¹, front contact 46 of relay FP¹, front contact 47 of relay FT¹, conductor 83 and winding of relay FTP¹, to (−). Relay FTP¹ closes a stick circuit for itself extending from (+), front contact 48 of relay FT¹, conductor 84, front contact 49 and winding of relay FTP¹, to (−).

A pick-up circuit is closed for relay BT¹, extending from (+), front contact 31 of relay 1SI¹, front contact 32 of relay FP¹, conductor 85 and winding of relay BT¹, to (−). The picking up 40 of relay FP¹ closes a stick circuit for relay 2SI¹ which is effective before relay SAP¹ picks up and opens its back contact 67 to open the pick-up circuit of relay 2SI¹. This stick circuit extends from (+), front contact 33 of relay FP¹, front contact 45 45 of relay 2SI¹, front contact 36 of relay 1SI¹ and lower winding of relay 2SI¹, to (−).

The opening of back contact 46 of relay FP¹ opens the circuit of relay FT¹ and this latter relay drops after a time interval which is determined by its slow acting characteristics. The opening of contacts 47 and 48 of relay FT¹ deenergizes relay FTP¹ and this relay is dropped in turn.

The closure of front contact 123 of relay FP¹ 55 closes an obvious pick-up circuit for relay SA¹ and the closure of front contact 124 of relay SA¹ closes an obvious pick-up circuit for relay SAP¹. During the impulsion of the line circuit and the consequent operation of contact 122 of relay F¹, relay FP¹ is energized when contact 122 is in its 60 left hand dotted position and when this contact is in its right hand position, the circuit for energizing relay FP¹ extends through front contact 125 of relay SAP¹. The positive energy provided 65 from (+) through front contact 126 of relay SAP¹, which extends through the front or back contact 127 of relay FP¹, is for the purpose of controlling the pick-up and stick circuits of the stepping and half step relays, such circuits being completely 70 shown in the above mentioned prior application Ser. No. 635,062. As above mentioned, relay VP¹ is picked up during the conditioning "on" period. An additional stick circuit is now closed for relay 2SI¹ which is independent of front contact 33 of 75 relay FP¹ and which extends from (+), front

contact 68 of relay VP¹, back contact 69 of relay 2V¹, conductor 86, front contact 34 of relay 2SI¹, front contact 36 of relay 1SI¹ and lower winding of relay 2SI¹, to (−).

Transmission of sending station code

It will be assumed that the typical field station illustrated applies the following code to the line:— Step 1—long "off", short "on". Step 2—Short "off", long "on". Step 3—short "off", short "on". This is determined by the first step code jumpers 231 and 241 being connected to (+), the second step code jumpers 232 and 242 being disconnected from (+) and the third step code jumpers 233 and 243 being disconnected from (+) and connected to (+) respectively, all as illustrated in Fig. 2B. It will be understood that this code is transmitted during a cycle, during which relays SA¹ and SAP¹ are picked up.

The code jumpers illustrated in Fig. 1B must correspond to those of Fig. 2B so that this station can check the code combination applied to the line by itself and by other stations to determine if its code is superior or inferior. Thus, the first step code jumpers 131 and 141 are connected to the long "off" and short "on" buses respectively. The second step code jumpers 132 and 142 are connected to the short "off" and long "on" buses respectively. The third step code jumpers 133 and 143 are connected to the short "off" and short "on" buses respectively. It is to be understood that there must be a similar correspondence at other stations between the code jumpers, similar to those of Fig. 2B and the code jumpers, similar to those of Fig. 1B.

The end of the conditioning "on" period, and the beginning of the first "off" period is marked by the control office circuits functioning to pick up relay PL. This is due to relay VP in the office picking up (in synchronism with relay VP¹ at the station) and indirectly controlling the energization of relay PL as clearly disclosed in application 635,062. The picking up of relay PL opens the line at back contact 28. This drops relay F¹ to its neutral position, which in turn drops relay FP¹ when contact 122 leaves its actuated position. A circuit is now closed for picking up relay 1V¹, which circuit is not shown in the present drawings.

Since it is assumed that the No. 1 "off" period 50 is long, as determined by jumper 231 being connected to (+), a circuit is now effective to pick up relay PB¹ which extends from (+), long "off" conductor 220, jumper 231, front contact 221 of relay 1V¹, back contact 222 of relay 2V¹, front 55 contact 203 of relay VP¹, conductor 82, front contact 204 of relay PT¹, front contacts 205 and 206 of the SI relays, back contact 207 of relay FP¹ and winding of relay PB¹, to (−). Since relay PT¹ is picked up at this time, the above described stick circuit for relay PB¹, including front contact 208 of relay PT¹, is again established. A circuit is closed for picking up relay FT¹, which extends from (+), front contact 45 of relay 2SI¹, back contact 46 of relay FP¹ and winding of relay 60 FT¹, to (−).

The picking up of relay PB¹ opens the circuit of relay PT¹ at back contact 213, allowing this latter relay to be released. The opening of contacts 204 and 208 of relay PT¹ opens the pick-up 70 and stick circuits of relay PB¹, which drops after a comparatively long interval of time due to the slow acting characteristics of this relay. This slow release of relay PB¹ maintains the line circuit open at back contact 63 for a comparatively 75

long interval for providing the long "off" assumed for this portion of the code.

When relay FP¹ closes its back contact 32 a circuit is established for picking up relay BTP¹ 5 extending from (+), front contact 31 of relay SI¹, back contact 32 of relay FP¹, conductor 87, front contact 37 of relay BT¹ and winding of relay BTP¹, to (-). The closure of front contact 38 of relay BTP¹ establishes a stick circuit for this 10 relay extending from (+), front contact 39 of relay BT¹, front contact 38 and winding of relay BTP¹ to (-). The opening of front contact 32 of relay FP¹ deenergizes the winding of relay BT¹ so that this relay drops during the long "off" 15 period provided by the delayed dropping of relay PB¹. The dropping of relay BT¹ opens the pick-up and stick circuits of relay BTP¹ allowing this latter relay to be released during the first "off" (long) period. 20 The closure of back contact 63 of relay PB¹ closes the line circuit at the field station. It will be understood that the office attempts to energize the line before relay PB¹ has dropped its contacts, in an attempt to provide a normally 25 short "off" period. Therefore, since the line circuit is now closed at the field station and in the control office, it is energized. This results in picking up relay F¹, which in turn picks up relay FP¹ over the previously described circuit. 30 It will be understood that during the interval of time when front contact 123 of relay FP¹ is open, relay SA¹ does not have time to drop its contacts due to its slow acting characteristics. The picking up of relay FP¹ during the first "on" 35 period again picks up relay PT¹ over the previously described circuit including front contact 214 and relay PT¹ is stuck up as before. Relay VP¹ is dropped during the first "on" period.

The timing relays in the control office open the 40 line circuit to terminate each "on" period after a comparatively long interval of time. Since it is assumed that the first "on" period is short, as determined by code jumper 241 being connected to (+), the field station opens the line before the 45 control office measures off its predetermined time interval. This is accomplished by the picking up of relay PF¹ immediately after relay VP¹ drops, over a circuit extending from (+), short "on" conductor 230, jumper 241, front contact 223 of 50 relay 1V¹, back contact 224 of relay 2V¹, back contact 225 of relay VP¹, conductor 88, front contacts 226 and 227 of the SI relays, front contact 228 of relay FP¹ and winding of relay PF¹ to (-). Relay PF¹ opens the line at its back contact 62 to mark 55 the end of the first "on" period and the beginning of the second "off" period.

Referring back to the first "on" period, relay FTP¹ is picked up and stuck up over the previously described circuits including front contacts 60 47 and 48 of relay FT¹. During the first "on" period relay BT¹ is again picked up over its previously described pick-up circuit in readiness to check the length of the next (second) "off" period. The opening of the line at the end of the first 65 "on" period causes relay F¹ to drop its contacts, which in turn drops relay FP¹, after which relay 2V¹ is picked up. Relay PF¹ is dropped in the second "off" period by the opening of front contact 228 of relay FP¹ in readiness to be picked 70 up or not, as determined by the second "on" jumper connection. Relay FT¹, due to its slow acting characteristics, does not have time to drop during the No. 1 "on" period which was assumed to be of short duration and it remains picked up 75 throughout the succeeding (second) "off" period

over the circuit including back contact 46 of relay FP¹.

Relay BTP¹ is again picked up and stuck up during the second "off" period by means of its previously described pick-up and stick circuits. 5 The second "off" period is assumed to be short (normal duration) as determined by the control office closing up the line at back contact 28 of relay PL after the proper time has been measured off by the office timing relays. This "off" 10 period is not made abnormally long, because jumper 232 of Fig. 2B, selected by front contact 234 of relay 2V¹, is disconnected from conductor 220 which leads to (+). During this comparatively short "off" period relay BT¹ does not drop 15 its contacts, because front contact 32 of relay FP¹ does not remain open for a sufficiently long interval of time to allow relay BT¹ to drop its armature. When the office closes up the line to mark the end of the second "off" period and the 20 beginning of the second "on" period, the closure of front contact 32 of relay FP¹ reenergizes relay BT¹ before it has had time to drop its contacts.

Relay VP¹ is picked up during the second "on" 25 period. Since code jumper 242 of Fig. 2B, as selected by front contact 244 of relay 2V¹, is disconnected from conductor 230, the second "on" period will be normally long. This is determined by the transmitting field station not opening the 30 line as before, but waiting for the control office to open the line. During the second "on" period relay FT¹, being deenergized at back contact 46 of relay FP¹, has time to drop its contacts which opens the pick-up and stick circuits of relay 35 FTP¹, allowing this relay to drop its contacts in turn.

When the control office opens the line to mark the end of the second "on" period and the beginning of the third "off" period, relays F¹ and 40 FP¹ are dropped and relay 3V¹ is picked up. Relay FT¹ is again picked up over the previously described circuit including back contact 46 of relay FP¹. Since it is assumed that the third "off" period is of normally short duration, relay 45 BT¹ does not have time to drop its contacts and relay BTP¹ remains stuck up. The third "off" period is short because the line is immediately energized when the control office closes the line to mark the end of the third "off" period and the 50 beginning of the third "on" period. This is due to jumper 233, as selected by front contact 236 of relay 3V¹, being disconnected from conductor 220 so that the field station does not interrupt the line circuit but allows the control office to energize 55 it in a normally short interval of time.

The energization of the line picks up relays F¹ and FP¹ and drops relay VP¹. Relay FTP¹ is again picked up and stuck up by means of the previously described circuits. Since jumper 243, 60 as selected by front contact 246 of relay 3V¹, is connected to (+) on conductor 230, relay PF¹ is picked up over a circuit extending from (+) on conductor 230, jumper 243, front contact 246 of relay 3V¹, back contact 247 of relay 4V¹, back 65 contact 225 of relay VP¹, conductor 88, front contacts 226 and 227 of the SI relays, front contact 228 of relay FP¹ and winding of relay PF¹, to (-). The opening of back contact 62 of relay PF¹ opens the line at the field station before 70 waiting for the control office to open it, which provides an abnormally short third "on" period. Relay FT¹ is not dropped during the third "on" period because back contact 46 of relay FP¹ is closed up for reenergizing relay FT¹ before it has 75

time to drop its contacts. The opening of the line at the end of the third "on" period marks the beginning of the fourth "off" period and permits relays F^1 and FP^1 to drop.

It will be understood that this operation may be continued for as many steps as required to provide the code combination for registering the transmitting station in the control office. It will also be understood that additional steps will be provided for selecting the short and long "on" and "off" code combinations by way of indication relay contacts or the like, instead of jumpers for providing the code which transmits the required conditions from the registered station to the control office.

The above explanation sets forth the manner in which the typical field station illustrated applies its code combination of long and short "off" and "on" periods as determined by the connections of its jumpers 231 , 232 , 233 , 241 , 242 and 243 . The manner in which the transmitting station is registered in the control office by the reception of this code combination may be, for example, as fully disclosed in the above mentioned prior application Ser. No. 645,037. From the above example it will be obvious that alternate codes can be applied at each step by the alternate connection (or disconnection) of the jumpers so that all stations can provide code combinations which differ from each other.

Plurality of stations simultaneously transmitting

In the event that there are two or more stations with new indications to transmit when the system is at rest (SAP relays down), there will be two or more change repeating relays up which causes the SI relays at the associated stations to be picked up and stuck up in a manner obvious from the above explanation of this operation. They remain stuck up throughout the conditioning period of the cycle and are dropped out at the inferior stations during the succeeding "off" and "on" periods as determined by the correspondence between the code jumpers such as 131 , 132 , 133 , 141 , 142 and 143 of Fig. 1B and the length of the corresponding "off" and "on" periods of the cycle.

After the last station selecting step has been taken, only one pair of SI relays such as relays $1SI^1$ and $2SI^1$ will remain picked up during the remainder of the cycle. Only at the station at which these two relays remain up are the succeeding steps of the cycle effective to transmit code impulses in accordance with the positions of the various devices at this particular station. At those stations which are dropped out due to inferior codes, the indication circuits are disconnected from the PB and PF relays. The "on" indication circuits are disconnected from the PF relays at contacts similar to 226 and 227 of relays $2SI^1$ and $1SI^1$ respectively. The "off" indication circuits are disconnected at contacts similar to 205 and 206 of relays $2SI^1$ and $1SI^1$. The PT relays at those stations are picked up but have no effect on the other circuits since the circuits leading off to the left from contacts 208 and 204 are incomplete.

Dropping out inferior stations

In the above example it was assumed that the code applied to the line circuit is long "off", short "on", short "off", long "on", short "off" and short "on". Those stations having their SI relays picked up at the start of the cycle and having the first "off" code jumper similar to 131 connected to long "off" bus similar to 136 will re-

main actively associated with the line during this first "off" period. This is because the FP relays open their front contacts similar to 32 for a sufficiently long interval of time to drop the BT relays and thereafter the BTP relays at these stations, so that a selecting stick circuit is maintained for the SI relays over a circuit similar to that extending from (+), back contacts 40 and 41 of relays $3V^1$ and $2V^1$ respectively, front contact 42 of relay $1V^1$, jumper 131 , bus 136 , back contact 134 of relay BTP^1 , conductor 81 , front contacts 43 and 44 of relays $2SI^1$ and $1SI^1$ respectively and lower winding of relay $1SI^1$, to (-). It is obvious that the $2SI$ relays are stuck up through front contacts similar to 33 of relay FP^1 during the "on" period (first) following the first "off" period of the cycle.

It will be apparent from the previous explanation that relays such as BTP^1 are down throughout an "on" period when the previous "off" period is long and these relays are up throughout an "on" period when the previous "off" period is short. Similarly the relays similar to FP^1 are down throughout an "off" period when the previous "on" period is long and they are up throughout an "off" period when the previous "on" period is short.

All stations actively associated with the line circuit during the first "off" period have their BTP relays down throughout the first "on" period. This is because the first "off" period is sufficiently long to drop the BT relays, due to the front contacts similar to 32 of the FP relays being open for a comparatively long interval. This dropping of the BT relays opens the pick-up and stick circuits of the BTP relays at all transmitting stations, allowing these latter relays to be dropped. At the beginning of the first "on" period the picking up of the FP relays will not drop the SI relays at stations with a No. 1 long "off" code due to a circuit similar to that extending from (+), back contact 40 of relay $3V^1$, back contact 41 of relay $2V^1$, front contact 42 of relay $1V^1$, jumper 131 , bus 136 , back contact 134 of relay BTP^1 , conductor 81 , front contact 43 of relay $2SI^1$, front contact 44 and lower winding of relay $1SI^1$, to (-).

At those stations having the first "off" jumper similar to 131 connected to the short "off" bus similar to 137 , the opening of front contact similar to 134 of the BTP relays opens the selective stick circuits of the $1SI$ relays and since the FP relays disconnect (+) from the stick circuits at back contacts similar to 33 , there are no energizing circuits to hold these $1SI$ relays in their picked up positions. The dropping of the $1SI$ relays opens up the stick circuits of the $2SI$ relays at front contacts similar to 36 and consequently both SI relays are dropped at inferior stations.

In the above example the second "off" period is short. At those stations with a jumper connection similar to 132 of Fig. 1B, the SI relays will be stuck up over circuits similar to that extending from (+), back contact 40 of relay $3V^1$, front contact 41 of relay $2V^1$, jumper 132 , bus 137 , front contact 134 of relay BTP^1 and over the remainder of the previously described circuit through the lower windings of the $1SI$ relays. Therefore, the $1SI$ relays will remain stuck up during the second "on" period after the FP relays open their back contacts similar to 33 , at those stations with a jumper connection similar to 132 .

Still assuming that one or more other stations are using the line during this cycle, then if one

of these other stations transmits a second long "off" indication those stations having a short "off" code combination for this step are dropped out because the long "off" is superior to the short 5 "off". Such a long "off" combination keeps the line circuit deenergized long enough to drop the BT and BTP relays for switching the contacts similar to 134 from the short "off" bus to the long "off" bus. Therefore, at those stations with 10 a second long "off" code the selective stick circuits of the ISI relays are completed through back contacts similar to 134 of the BTP relays. At those stations having a second short "off" code these selective stick circuits are not completed because the BTP relays at all stations drop and by the opening of front contacts similar to 15 134, the selective stick circuits of the SI relays at those stations where the jumpers similar to 132 do not connect to the long "off" buses are 20 interrupted.

It is believed that the above examples of the manner in which the SI relays are maintained in their energized positions at superior stations and dropped at inferior stations, as well as the explanation of the checking of the long and short 25 "off" indications in connection with the first two codes, are sufficient to give an understanding of the operation of this feature of the invention at additional steps of the cycle.

30 It will be recalled that the assumed code combination provides a first short "on" and a second long "on". It will now be explained how these two combinations are checked at the field stations so that those stations with a short "on" combination remain on the line in preference to those with a long "on" combination. The FT and FTP relays check the timing of the "on" periods of the cycle. Relay FT¹ is not dropped during a short 35 "on" period because back contact 46 of relay FP¹ is closed at the end of the "on" period in a comparatively short interval of time after this contact is opened at the beginning of the "on" period.

It will be recalled that relay FT¹ remains picked up throughout the second "off" period over a circuit through back contact 46 of relay FP¹ and that relay FTP¹ is picked up during the first "on" period. Since relay FT¹ is not dropped, relay 40 FTP¹ remains stuck up through the succeeding (second) "off" period over a circuit including front contacts 48 and 49 of relays FT¹ and FTP¹. This results in relay FTP¹ remaining picked up throughout the second "off" period because the first "on" period is of short duration.

45 The above discussion relating to relays FT¹ and FTP¹ also applies to similar relays at other stations which are transmitting. At those stations having a code jumper connection similar to 141, the 2SI relays will remain stuck up during 50 the second "off" period over a circuit similar to that extending from (+), back contact 68 of relay VP¹, back contact 70 of relay 3V¹, front contact 71 of relay 1V¹, jumper 141, bus 72, front contact 73 of relay FTP¹, conductor 86, front contact 34 of relay 2SI¹, front contact 36 of relay 55 ISI¹ and lower winding of relay 2SI¹, to (-). It will be obvious that relay ISI¹ remains stuck up during the second "off" period by way of the previously described circuit to (+) at back contact 33 of relay FP¹ and this of course applies also to all stations which are transmitting.

At those stations where the jumpers similar to 60 141 are connected to the long "on" buses similar to 14, the opening of back contacts similar to 70 75 73 of relay FTP¹ interrupts the above described

stick circuits for the 2SI relays and these relays are released.

The second long "on" code combination causes the dropping of the FT relays because the FP relays have their back contacts similar to 46 open for a sufficient interval of time to allow the FT relays to drop. This drops the FTP relays by opening their pick-up and stick circuits during the second "on" period. At those stations where the jumpers similar to 142 connect to the long 10 "on" buses, the selective stick circuits of the 2SI relays are completed over circuits similar to that extending from (+), front contact 68 of relay VP¹, front contact 69 of relay 2V¹, jumper 142, bus 14, back contact 73 of relay FTP¹, conductor 86, front contact 34 of relay 2SI¹, front contact 36 of relay ISI¹ and lower winding of relay 2SI¹, to (-). The ISI¹ relays are stuck up during the "off" period over a circuit similar to that extending through back contact 33 of relay FP¹, front contacts 43 and 44 of relays 2SI¹ and ISI¹ respectively and the lower winding of relay ISI¹, to (-).

If there is a station transmitting a second short "on" indication, then the station or stations with a long second "on" code combination are dropped out. This is because the line is not energized for a sufficient interval of time to drop the FT and FTP relays. Therefore, at those stations where the jumper similar to 142 is connected to the short 25 "on" buses, the selective stick circuits of the 2SI relays are completed through the front contacts similar to 73 of relay FTP¹. At those stations with a long "on" code combination the jumpers similar to 142 are connected to the back contacts similar to 73 of relay FTP¹ by way of the long "on" buses, so that the selective stick circuits of the 2SI relays at these stations are incomplete 30 because the FTP relays do not drop at these stations.

35 It is believed that the above examples relating to the checking of both a short and a long "on" code combination and the manner in which those stations with long "on" combinations are dropped out when the system transmits short "on" combinations at particular steps is sufficient to indicate how this portion of the invention operates for additional steps.

40 When the system takes the next step after the station selecting step by picking up relay 4V¹, permanent stick circuits are provided for the SI relays. The permanent stick circuit for relay 2SI¹ extends from (+), front contact 75 of relay 4V¹, conductor 86, front contact 34 of relay 2SI¹, front contact 36 of relay ISI¹ and lower winding of 45 relay 2SI¹, to (-). The permanent stick circuit for relay ISI¹ extends from (+), front contact 76 of relay 4V¹, conductor 84, front contact 43 of relay 2SI¹, front contact 64 of relay ISI¹ and lower winding of relay ISI¹, to (-). It will of course 50 be understood that when the stepping relays are dropped at the end of the cycle these permanent stick circuits are deenergized so that the SI relays are restored to normal.

45 After the individual station has been selected by dropping out all SI relays except those associated with the most superior calling station as above discussed and the registration of this station in the control office as disclosed in the above mentioned prior application Ser. No. 645,037, additional code impulses are transmitted to the control office as determined by the conditions of the various devices at the calling station. The manner in which this operation is effected, as well as the manner of restoring the system to normal 55 70 75 76

inferior station thereafter opening said line during said operating cycle.

9. In a centralized traffic controlling system for railroads, a control office and a plurality of field stations, a line circuit connecting said office with said stations, means in the control office for applying normally time spaced impulses of normal length to said line circuit, code forming means at each of said stations for at times varying the lengths of said impulses and said time spaces between said impulses, a first station selecting relay at each station selectively controlled by said time spaces, a second station selecting relay at each station selectively controlled by said impulses, and means controlled by said relays in combination for selectively controlling said code forming means.

10. In a centralized traffic controlling system for railroads, a line circuit connecting a control office and a plurality of field stations, means at the control office for applying uniformly time spaced impulses of uniform length, code transmitting means at each station operable to change the length of selected ones of said impulses and said time spaces in accordance with a distinctive code call for that station, code responsive means at each station selectively controlled by the varied lengths of said impulses and said time spaces for rendering said code transmitting means ineffective at that station whenever the variation in lengths of said impulses and said time spaces fail to match the distinctive code call for that station, and means in the control office responsive to the varied lengths of said impulses and said time spaces to register the resulting code call.

11. In a centralized traffic controlling system for railroads, a line circuit connecting a control office and a plurality of field stations, means at the control office for applying a series of uniformly time spaced impulses of uniform length, code transmitting means at each station at times operable to selectively shorten the length of said impulses and to selectively lengthen the duration of said time spaces in accordance with a distinctive code call for that station by opening and closing said line circuit, code responsive station selecting means at each station selectively controlled by the varied lengths of said impulses and said time spaces on said line circuit for rendering said code transmitting means ineffective at that station whenever the variation in lengths of said impulses and said time spaces fail to match the distinctive code call for that station, and means in the control office responsive to the varied lengths of said impulses and said time spaces to register the resulting code call, whereby the code responsive station selecting means at only one station is conditioned for the selection of that station at the end of said series and the corresponding code call for that station is registered in the control office.

12. In a centralized traffic controlling system for railroads, a control office and a plurality of field stations, a line circuit connecting said office with said field stations, means in the control office for applying a plurality of series of normally time spaced impulses of normal length to said line circuit, means for simultaneously recording at a plurality of stations the condition that indications await transmission to said office from said stations, means at each station responsive to said simultaneous recording for selecting said stations in rotation by modifying said series of impulses to form a code of variably time spaced impulses of variable length

over said line circuit characteristic of that station, and means at each station controlled by the length of the impulses of each series characteristically modified to form a code for determining the order of selection for that station.

13. In a centralized traffic controlling system for railroads, a control office and a plurality of field stations, a line circuit connecting said office with said field stations, means in the control office for applying a plurality of series of normally time spaced impulses of normal length to said line circuit, means for simultaneously recording at a plurality of stations the condition that indications await transmission to said office from said stations, means at each station responsive to said simultaneous recording for selecting said stations in rotation by modifying said series of impulses to form a code of variably time spaced impulses of variable length over said line circuit characteristic of that station, and means at each station controlled by the length of the spaces between impulses and by the length of the impulses of each series characteristically modified to form a code for determining the order of selection for that station.

14. In a centralized traffic controlling system for railroads, a control office and a plurality of field stations, a line circuit connecting said office with said field stations, means in the control office for applying a plurality of series of normally time spaced impulses of normal length to said line circuit, means for simultaneously recording at a plurality of stations the condition that indications await transmission to said office from said stations, means at each station responsive to said simultaneous recording for selecting said stations in rotation by modifying said series of impulses to form a code of variably time spaced impulses of variable length over said line circuit characteristic of that station, and means at each station controlled by the length of the spaces between impulses and by the length of the impulses of each series characteristically modified to form a code for determining the order of selection for that station.

15. In a centralized traffic controlling system for railroads, a control office and a plurality of field stations, a line circuit connecting said office with said stations, means in the control office for applying a plurality of series of normally time spaced impulses of normal length to said line circuit, station selecting means at each station, a step-by-step mechanism at each station for selecting a plurality of code connections, means controlled by any series of time spaced impulses on said line circuit for advancing said mechanism through an operating cycle, means at each station for modifying said series of impulses to form a code of variably time spaced impulses of variable length transmitted over said line circuit characteristic of that station, and means at each station controlled by the length of said impulses and the succeeding time spaces of any particular series of impulses for energizing said station selecting means only at the station where the selected code connections correspond to the lengths of said impulses and the time spaces between said impulses.

at the end of each cycle, is immaterial to an understanding of the present invention and is not illustrated but may be accomplished, for example, in the same manner as disclosed in the above 5 mentioned application, Ser. No. 645,037.

Having thus shown and described a centralized traffic controlling system for railroads as one specific embodiment of the present invention, it is desired to be understood that this form is 10 selected to facilitate in the disclosure of the invention rather than to limit the number of forms which it may assume and it is further to be understood that various modifications, adaptations and alterations may be applied to the specific form 15 10 shown to meet the requirements of practice without in any manner departing from the spirit or scope of the present invention except as limited by the appended claims.

Having described our invention, we now claim:

20 1. In a centralized traffic controlling system for railroads, a control office and a plurality of field stations, a line circuit connecting said office with said stations, means in the control office for applying time spaced impulses of current to said line

25 circuit, code selecting means at each station operable to selectively change or leave unchanged the length of said impulses and the time spaces between said impulses, and means at each of said stations responsive to the code formed by said 30 impulses and said time spaces on said line circuit only when such code corresponds to the code formed by said code selecting means at that station.

2. In a centralized traffic controlling system for 35 railroads, a control office and a plurality of field stations, a line circuit connecting said office with said stations, means in the control office for applying impulses of current of uniform length to said line circuit separated by uniform time space 40 intervals, means at each station for at times shortening the length of selected ones of said impulses, and means at each of said stations distinctively responsive to the length of said impulses.

45 3. In a centralized traffic controlling system for railroads, a control office and a plurality of field stations, a line circuit connecting said office with said stations, means at the control office for applying impulses of current of uniform length to said line circuit separated by uniform time space intervals, means at each station for at times shortening the length of selected ones of said impulses, means at each station for at times extending selected ones of said time space intervals, 50 and means at each of said stations distinctively responsive to the resulting lengths of said impulses and said time space intervals on said line circuit.

60 4. In a centralized traffic controlling system for railroads, a control office and a plurality of field stations, a line circuit connecting said office with said stations, means in the control office for applying normally time spaced impulses of normal length to said line circuit, a plurality of stepping 65 relays at each field station operated sequentially by said impulses, means at each station controlled by the associated stepping relays for selectively opening said line circuit during a time space period between said impulses for extending such 70 period, means at each station controlled by the associated stepping relays for selectively opening said line circuit during an impulse period, means at each station operable to close said line circuit after said time space has been abnormally ex-

tended, and means at each station responsive only to an abnormally shortened impulse period.

5. In a centralized traffic controlling system for railroads, a control office and a plurality of field stations, a line circuit connecting said office with said stations, means in the control office for applying normally time spaced impulses of normal length to said line circuit, a plurality of stepping relays at each field station operated sequentially by said impulses, means at each station controlled by the associated stepping relays for selectively opening said line circuit during a time space period between said impulses, means at each station controlled by the associated stepping relays for selectively opening said line circuit during an impulse period, means at each station operable to close said line circuit after said time space has been abnormally extended, means in said office operable to open said line circuit after said impulse period has been abnormally shortened, and means at each station responsive only to an abnormally extended time space and an abnormally shortened impulse period.

20 6. In a centralized traffic controlling system for railroads, a control office and a plurality of field stations, a line circuit connecting said office with said stations, means in the control office for applying normally time spaced impulses of normal length to said line circuit, means at each of said stations for at times conditioning said line circuit with a superior condition during selected ones of said impulses whereby the lengths of selected impulses are changed from normal to abnormal, means at each of said stations for conditioning said line circuit with an inferior condition during selected ones of said impulses, and means at each station responsive to said superior condition for canceling an inferior condition imposed upon said line circuit by that station.

25 7. In a centralized traffic controlling system for railroads, a control office and a plurality of field stations, a line circuit connecting said office with said stations, means in the control office for applying normally time spaced impulses of normal length to said line circuit, means at each of said stations for at times conditioning said line circuit with a superior condition during selected ones of said impulses and selected ones of said time spaces whereby the length of an impulse is 30 changed from normal to abnormal and a time space between impulses is changed from normal to abnormal, means at each of said stations for at times conditioning said line circuit with an inferior condition during selected ones of said impulses and selected ones of said time spaces, and means at each station controlled by said superior condition for canceling an inferior condition imposed upon said line circuit by that station.

35 8. In a centralized traffic controlling system for railroads, a control office, a superior field station and an inferior field station, a single circuit line connecting said office with said stations, means in said office for opening and closing said line during an operating cycle for applying uniformly time spaced impulses of uniform length thereto, means at each of said stations for opening and closing said line whereby it is distinctively conditioned for each impulse and for each time 40 space between impulses, means effective to permit both of said stations to open and close said line during a portion of said cycle, and means controlled by the opening and closing of said line by said superior station for preventing said 45 line from being closed during a portion of said cycle.
